LAUNDRY TUB UNIT

Bernard E. Mustee, Cleveland, Ohio, assignor to E. L. Mustee & Sons, Inc., a corporation of Ohio

Application September 10, 1954, Serial No. 32,245

Term of patent 14 years

(Cl. D49—1)

Fig. 1

Fig. 2

The rear and side walls of the tub portion not shown in the drawing are plain and substantially identical to those walls which are shown.

I claim:

The ornamental design for a laundry tub unit, as shown and described.
